UNITED STATES PATENT OFFICE.

CHARLES M. ROBBINS, OF ATTLEBORO, MASSACHUSETTS, ASSIGNOR TO THE
CHARLES M. ROBBINS COMPANY, A CORPORATION OF RHODE ISLAND.

DESIGN FOR A BADGE OR SIMILAR ARTICLE.

SPECIFICATION forming part of Design No. 35,406, dated December 10, 1901.

Application filed November 18, 1901. Serial No. 82,802. Term of patent 7 years.

To all whom it may concern:

Be it known that I, CHARLES M. ROBBINS, a citizen of the United States, residing at Attleboro, in the county of Bristol and State of

Massachusetts, have invented and produced a new and original Design for a Badge or Similar Article, of which the following is a specification.

Figure 1 is a front elevation of a pin-badge embodying my design, and Fig. 2 an edge view of the same.

As shown in the drawings, the leading or material feature of my design consists of an arched rope pendent from a simitar and grasped on either side by a hand.

In detail the upper portion of the badge consists in the representation of a simitar *a*, from the blade of which, suspended by a link

b, is pendent the representation of an arched rope *c*. Grasping the rope on either side and below the curve of the arch is the representation of a hand *d d*.

It is apparent that my design is applicable to button-badges as well as pin-badges.

Having thus described my invention, what I claim as new, and desire to secure by Letters Patent, is—

The design for a badge or similar article, as herein shown and described.

In testimony whereof I have affixed my signature in presence of two witnesses.

CHARLES M. ROBBINS.

Witnesses:

CHAS. L. TAYLOR,
HORATIO E. BELLOWES.
